UNITED STATES PATENT OFFICE.

CHARLES E. THOMPSON, OF LANSINGBURG, NEW YORK.

DESIGN FOR A BRUSH.

SPECIFICATION forming part of Design No. 17,282, dated April 26, 1887.

Application filed February 17, 1887. Serial No. 228,007. Term of patent 7 years.

To all whom it may concern:

Be it known that I, CHARLES E. THOMPSON, a citizen of the United States, residing at Lansingburg, in the county of Rensselaer and State of New York, have invented and produced a new and original Design for Brushes, of which the following is a specification, reference being had to the accompanying drawing, forming part thereof.

10 The drawing represents a view in perspective of my newly-designed brush.

My new design relates to that class of brushes known as "daubers," used to apply blacking to boots and shoes or other articles.

15 My design consists in the configuration of the head-band B, provided with the triangular shaped projecting spur D and loop-handle A, which together resemble the form of the figure 8, when one of the loops of the figure is circular and the other is elongated in the direction of a line bisecting both loops. The shape

of the head-band is that of the circular loop of the figure, and the shape of the handle that of the elongated loop of the figure.

When desired, the spur D may be omitted 25 without affecting the entirety of my design.

I claim—

The herein-described design for a brush, in which the general configuration of the head-band B and handle A is that of the figure 8, 30 when one of the loops of the figure, representing the head-band, is circular and the other loop, representing the handle, is elongated in the direction of a line bisecting both loops, and the head-band is provided with a projecting triangular-shaped spur, D, substantially as shown and described.

January 31, 1887.

CHAS. E. THOMPSON.
